UNITED STATES PATENT OFFICE.

EUGENE F. COOK, OF ST. LOUIS, MISSOURI, ASSIGNOR TO LOUIS H. KUHLMANN, OF ST. LOUIS, MISSOURI.

COILED METAL WEATHER-STRIPPING

1,202,487.

Specification of Letters Patent.

Patented Oct. 24, 1916.

Application filed January 12, 1916. Serial No. 71,625.

To all whom it may concern:

Be it known that I, EUGENE F. COOK, a citizen of the United States, residing in the city of St. Louis and State of Missouri, have 5 invented new and useful Improvements in Coiled Metal Weather-Stripping, of which the following is a specification.

This invention relates to a coil of weather strip as an article of manufacture, and to 10 the method of producing the same.

The invention relates to that type of metal weather strip in which the longitudinal edges of the strip are bent at an angle and also folded over and pressed flat to provide 15 a rounded edge. Prior to my invention it has been customary to deliver these strips to the consumer in straight lengths, as it had been found impossible to coil the same without causing the strip to buckle, so that when 20 applied in position on the door or window frame it would not present a perfectly flat, even surface for engagement with the edge of the door or window. The necessity of delivering these strips in straight lengths 25 has been the cause of great waste, as a portion of the strip must invariably be cut off in fitting it to door and window sashes of different sizes or heights, and the cut-off part is generally too short to be of any use. 30 To overcome the objection to coiling and to prevent the waste, incident to the use of metal weather strips furnished in straight lengths, I conceived the idea of rolling the strip in such manner that it could be readily 35 coiled, and of delivering the weather strip in coiled packages so that by the use of my invention it is now possible for the operator to remove from the coil just the length of strip desired and sever that length from 40 the remaining part of the coil without wasting any part thereof whatsoever.

The invention is illustrated in the accompanying drawing, in which—

Figure 1 is a broken view partly in section, and partly in side elevation, illustrating the manner of rolling the weather strip; Fig. 2 is a view in front elevation, on an enlarged scale, of the compression rollers shown in Fig. 1 with the strip between 50 them; Fig. 3 is a view in front elevation of the bending roller shown in Fig. 1; and Fig. 4 is a view, in end elevation, on an enlarged scale, illustrating the condition of the strip as to its bent edges as it enters between the 55 compression rollers shown in Fig. 1.

Referring now to the drawing, the numerals 1, 2, indicate two rollers keyed on respective shafts 3 and 4 by means of which they are rotated in any preferred manner, the shaft 3 being located slightly in advance 60 of the shaft 4 so that the meeting line of the two rollers will be slightly below a horizontal plane tangent to the circumference of the roller 2 at the upper side thereof.

The numeral 5 indicates an arm which is 65 pivotally mounted on a bearing 6 provided on a support 7, and which has rotatably mounted on its outer end a bending roller 8. The under side of this roller is normally at a considerable distance below the upper side 70 of the roller 2, and this distance can be adjusted, and when adjusted maintained, by a set screw 9 working through a support 10 carrying a binding nut 11.

As ordinarily practised the strip 12 is 75 first acted upon by a pair of rollers to partly bend over its longitudinal edges, as indicated at 13 in Fig. 4, and to slightly bend the outer edge portions of the strip in opposite directions, as indicated at 14. My invention is not concerned with this part of the operation except that it is a necessary step to the subsequent operations which I practise to enable the strip to be coiled. The strip bent to the form shown in Fig. 4 is 80 then passed between the rollers 1 and 2. These rollers, as shown by Fig. 2, are provided with corresponding, oppositely-disposed angular end portions 15 and 16, and with corresponding and oppositely-disposed 85 conoidal central portions 17. The angular end portions of the roller 2 are further cut away, as indicated at 18, 19, to provide a space to accommodate the bent-over end portions 13 of the strip, the entire opposed surfaces of the rollers being parallel to each other, as shown.

In order to adopt the strip to form a roll I extend one side or face of the strip relatively to the other. For this purpose the rollers 1 and 2 are adjusted sufficiently close 100 to each other to cause the end portions 13 to be pressed against the angular portions 14 of the strip as it passes between the two rollers, and as these rollers are off center, 105 the under circumferential edge portion of the upper roller being slightly below the upper circumferential edge portion of the lower roller, the strip 12 is given a slight downward bend or curve as it passes be- 110

tween the rollers, which is facilitated by the action of the roller 8, the position of which causes the strip to be turned downward so that as the strip is passed between 5 the rollers 1 and 2 and under the said roller 8 it is caused to be bent around a portion of the periphery of the roller 2. The surface of the roller 8 is shaped to correspond to the shape of the rollers 1 and 2, having 10 oppositely-disposed angular end portions 20, 21, and a conoidal central portion 22. The roller, however, is of much less diameter than the said rollers 1 and 2. This operation, as will be understood, causes a 15 slight uniform compression or condensation of the material on the under side of the bent-over portion 13 of the strip, and a corresponding stretching, extension or expansion of the material on the upper side of the 20 angular end portions 14 of said strip, and as this change occurs in a longitudinal direction in the strip, it results in imparting to the strip a natural tendency to coil, notwithstanding the angular bends in the strip. 25 At the same time the bending or compressing action upon the strip is so slight as not to prevent the strip when unwound and secured in position from extending in a perfectly straight line. As the strip passes 30 from under the roller 8 it is immediately wound upon a reel, indicated generally by 23, which may be operated in any suitable manner, either manually or by suitable driving mechanism, and when a coil of the desired size has been obtained by so winding 35 the strip, the latter is cut and its free end secured in any desired manner to the reel to prevent it from unwinding. The strip thus coiled into a roll may be furnished to 40 the user, who, as stated, will in practice remove from the coil just the length required in weather stripping an opening, and thus avoid waste. When the strip is unwound from the coil it will readily assume a practically straight position, and it will be found 45 that the coiling has not caused it to buckle or to be permanently bent or distorted.

While I have stated that the strip is

curved in passing between the rollers 1 and 2, and under the roller 8, this must be understood to refer largely to a temporary condition, the operation, in fact, resulting in putting the strip into a condition which will permit it to be coiled without buckling, or without causing the strip to be permanently bent or distorted rather than imparting a permanent curve to the strip. 50

I claim:

1. As a new article of manufacture, a coil of metal weather stripping, the latter having folded longitudinal edge portions. 60
2. As a new article of manufacture, a coil of metal weather stripping, the latter having angularly-disposed and folded longitudinal edge portions. 65
3. As a new article of manufacture, a coil of metal weather stripping, the latter having folded longitudinal edge portions and being characterized by freedom from permanent bends or distortions and from a 70 tendency to buckle when unwound. 75
4. As a new article of manufacture, a coil of metal weather stripping, the latter having angularly-disposed and folded longitudinal edge portions and being characterized by freedom from permanent bends and distortions and from a tendency to buckle when unwound. 80
5. As a new article of manufacture, a supply roll of metal weather stripping consisting of a continuous strip having longitudinal edge portions folded against the body of the strip, the material of said strip on one side being extended relatively to the other side of the strip to enable the strip 85 to assume an arcuate form. 90
6. As a new article of manufacture, a metal weather strip consisting of a continuous strip having longitudinal edge portions folded against the body of the strip and conditioned to enable the strip to assume an arcuate form when coiled into a supply roll.

In testimony whereof, I have hereunto set my hand.

EUGENE F. COOK.
